(57) **CLAIM**

We claim the ornamental design for a display screen with graphical user interface, as shown and described.

DESCRIPTION

The patent or application file contains at least one color drawing. Copies of this patent or patent application publication with color drawing will be provided by the USPTO upon request and payment of the necessary fee.

FIG. 1 is a perspective view of a display screen with graphical user interface showing our new design;

FIG. 2 is a front elevation view thereof; and,

FIG. 3 is an enlarged view of a portion of the image of FIG. 1. The broken lines shown in the drawings represent environmental structure that forms no part of the claimed design.
